UNITED STATES PATENT OFFICE

IRVING ALBERT TAYLOR, OF WORCESTER, MASSACHUSETTS, ASSIGNOR TO RILEY STOKER CORPORATION, OF WORCESTER, MASSACHUSETTS, A CORPORATION OF MASSACHUSETTS

PROTECTED GRATE BLOCK FOR STOKERS

Application filed July 9, 1924. Serial No. 724,962.

My invention relates to stokers and more particularly to the grate block construction of an underfeed stoker.

A stoker of the type shown in the patent 5 to Riley, No. 1,090,651, of March 17, 1914, has tuyère walls between retorts through which coal is fed by a suitable ram mechanism. These tuyère walls comprise two inclined side bars mounted side by side for alternate reciprocation in a horizontal direction, and grate blocks supported in a step-like formation on these side bars. The grate blocks are provided with small tuyère openings communicating with larger passages 15 within the block through which air is admitted to the fuel bed. It has been found that in the operation of such a furnace, the nose or fuel supporting portions of these grate blocks tend to burn off and therefore to 20 cause a change in the size of the tuyère openings and so affect the operation of the furnace.

It is accordingly the prime object of my invention to overcome this difficulty and to 25 provide an improved grate block construction which will not burn away readily and which will remain comparatively cool under normal operating conditions and thus remain efficient throughout a long period of service.

It is a further object of my invention to 30 provide a tuyère block which is so shaped that the air which issues through the tuyère may be caused to traverse a circuitous path in contact with the under side of the block 35 and so keep it cool.

Another object of my invention is to provide a grate block construction which will automatically catch and retain ashes on its surface and so provide an effective heat insulating coating thereon.

With these and other objects in view as will be apparent to one skilled in the art, my invention resides in the combination of parts set forth in the specification and covered by 45 the claims appended hereto.

Referring to the drawings which illustrate one embodiment of my invention, and in which like reference numerals indicate like parts;

50 Fig. 1 is an isometric view of a grate block

showing the top and side which are normally exposed to the heat of the fire.

Fig. 2 is a similar isometric view of the grate block turned upon its normally unexposed side so as to show the exposed side of 55 the block as well as the bottom thereof.

Fig. 3 is a cross section on the line 3—3 of Fig. 1.

Fig. 4 is a cross section on the line 4—4 of Fig. 1.

Fig. 5 is a side elevation broken away to show a side bar with a number of grate blocks mounted thereon.

Fig. 6 is a top plan view of one set of grate blocks shown in Fig. 5.

Fig. 7 is a fragmentary detail in horizontal section on the line 7—7 of Fig. 5.

Fig. 8 is a side elevation, similar to Fig. 5, of a modification.

Fig. 9 is a fragmentary section on the line 70 9—9 of Fig. 8 showing the tortuous air passage.

Fig. 10 is a cross section on the line 10—10 of Fig. 5; and

Fig. 11 is a perspective view of the block 75 shown in Fig. 8.

In accordance with my invention, I provide a tuyère block with a tortuous air passage so constructed that the air is caused to pass in contact with a considerable surface 80 of the block and so absorb heat therefrom, thus serving both to cool the block and to preheat the tuyère air. Also, I provide a block with pockets on the upper exposed surface of its nose or fuel supporting portion 85 which will collect slag and ashes and hold such heat insulating material in position to protect the block. One type of block embodying both of these features may be formed, as illustrated, with a central horizontal web provided with ribs on its upper and lower sides. Those on the upper side are located on the nose portion and are arranged transversely thereof so as to catch and hold material moving lengthwise of the grate 90 blocks in the stoker. The ribs on the under side are so arranged that in cooperation with the upper part of another block they form a labyrinth for the circuitous passage of air beneath a portion of the block, and prefer-

100

ably the nose portion so that the cooling air may be fed into the fuel bed at the end of the block.

As will be apparent from inspection of Fig. 5, Fig. 10, and the patent to Riley, two series of grate blocks 10 are mounted in step-like formation on two juxtaposed, inclined, reciprocable side bars 12 so as to form a tuyère wall and fuel supporting grate. It will be understood that the side bars incline downwardly from the upper front end of the stoker towards the ash dump and that the nose of the block is at the rear and faces the ash dump. The grate blocks have openings therethrough communicating with the space beneath the supporting side bar, and these openings connect with passages formed between the grate blocks in such a manner as to conduct air to the fuel bed through suitably located tuyère openings.

While this block may be constructed in various shapes and arrangements within the scope of my invention, the block as illustrated comprises a metal casting having a vertical side wall 15 which contacts with a like wall on the adjacent block in the other series. A wall 16 parallel with the side wall extends throughout substantially half of the block at the end covered by the block above, and is connected to the wall 15 by struts or walls 17 and 18 to form a hollow opening through which air may pass upwardly from beneath the side bars. A flange 20 connected with the wall 16 serves to restrict the size of the vertical opening 21 between walls 15 and 16, and in cooperation with the top of the wall 15 serves as a support for the block above.

Extending rearwardly from the wall 18 is a web 22 connected with the wall 15. In the form illustrated, the rear portion 23 of the web is substantially horizontal, the central part 24 is inclined at substantially the same angle as the rearward sloping portion 25 of the flange 20 and the forward portion 26 is substantially horizontal. As will be apparent from an inspection of Fig. 5, these grate bars are arranged one above the other with the web portions 23 and 24 exposed, and the web portion 26 beneath the portion 23 of the block above.

On the under side of the web 22 is a series of substantially parallel flanges which serve the double purpose of conducting heat away from the web portion and of forming a tortuous passage to maintain the circulating air in contact with the metal for a considerable length of time and thus absorb heat therefrom. The flanges 28 depending from web portions 24 and 26 are arranged and shaped to fit upon the flat portions 20 and 25 of the block beneath, but as will be observed by inspection of Figs. 2 and 3, the flanges do not extend all the way across the grate block but leave a space connecting with the opening 21 through the block beneath whereby air

may be fed to the nose end of the block. Since the side wall 16 does not extend above the flange 20, 25 air will issue laterally through the tuyère openings 29 (Fig. 5) formed by the flanges 28, the same as shown in the Riley patent.

Flanges 30 are arranged on the under side of the nose portion 23 of the web and these are adapted to fit against the web portion 26 between the walls 15 and 16 of the block beneath. For this purpose the flanges 30 are made slightly shorter than the width of the block, as shown in Figs. 2, 4 and 7, and in order to provide a labyrinth for the circulation of air, these flanges are set in a staggered formation and are arranged to be located above the web 26 of the block beneath, so that air may pass around the end of one and then to the opposite side of the block and around the end of another until it has reached the nose end of the block where it escapes through the opening 32 in the wall 33 which connects the walls 15 and 16 adjacent the nose end of the web portion 26 of the block beneath the labyrinth forming flanges. This opening 32 serves as a tuyère opening through which air is admitted to the fuel supported above.

A set of transverse flanges or ribs 36 are arranged on the upper side of the web 22, the top of these ribs being preferably on a line with the top of the rearward portion of the wall 15. These ribs are arranged in this position in order to catch slag and ash that form during combustion of the fuel and to hold this dead matter in position on the grate blocks and thus furnish an additional insulating means which tends to prevent destruction of the block by heat and oxidation. At the extreme tip of the nose, a further set of flanges 37 may be run longitudinally of the block for strengthening purposes, but if desired a lateral flange may be employed at the nose to catch the slag there as well as further up the block.

In accordance with the modification shown in Figs. 8, 9, and 11, I may extend the labyrinth forwardly as far as desired and thus provide for a longer contact of the circulating air with the block. As illustrated, the wall 38 corresponding with the wall 16 of Fig. 1 may be extended rearwardly to form a side wall above the flange portion 39 corresponding with part 25 (Fig. 1) and fit against the bottom of the web and side wall of a block above. The labyrinth forming flanges 40 depend from the under side of the web 41 and are staggered to provide a long passage for air from the front of the block nearest the side bar to the nose as indicated by the arrows. The front of the block has a passage 42 through the web 41 and communicates with the labyrinth over the end wall 43, as indicated in dotted lines in Fig. 8. Tuyère openings 44 of gradually decreasing size

from the front to the rear are formed in the side wall 38 opposite the labyrinth and the flanges 40 may be so spaced as to form a gradually narrowing passage from front to rear.

5 This insures a proper distribution of air to the side openings 44 and the rear opening 45 which corresponds with the opening 32 in Fig. 7.

It will now be apparent that I have provided an effective means for preventing rapid destruction of a grate block by insulating the top from the fire and cooling the under portion. Also, I insure a proper feeding of air to the fuel bed both laterally and at the nose 15 of the grate block. It will be evident from the above disclosure that various changes may be made in this construction without departing from the spirit and the scope of the appended claims.

20 Having thus described my invention, what I claim as new and desire to secure by Letters Patent is:

1. A grate block for a stoker comprising a substantially horizontal web, one end of 25 which has spaced transverse ribs on its upper side arranged to catch ashes and hold the same in position against the action of the fuel moving across the ribs lengthwise of the block and thereby form a heat insulating layer, and walls cooperating with the web to form an air channel, said air channel serving when the blocks are piled with other blocks in a step-like formation to admit air to the fuel bed supported thereon.

35 2. A grate block comprising a unitary casting having a longitudinal web portion, a set of depending flanges on the underside thereof and upwardly projecting walls on its upper side, said block being so constructed that 40 it may be piled with other blocks in step-like formation with the flanges on one block cooperating with the walls on another block to form a tortuous air passage and a tuyère to the fuel bed supported thereon.

45 3. A grate block for a stoker comprising a longitudinal web having ribs on the upper side of the rear portion thereof forming ash receiving pockets, flanges on the under side of the web, and walls on the upper front portion so constructed that when assembled in a 50 step-like formation two similar blocks will form a tortuous air channel therebetween, the walls at the front of the lower block defining an air inlet opening therethrough which communicates with the tortuous channel and said block having a tuyère opening through which air may pass after traversing the tortuous channel in cooling contact with the flanges.

4. A grate block for stokers adapted to be 60 piled with similar blocks in a step-like formation comprising a longitudinal web, a set of flanges on the under side thereof, and side walls cooperating with the web to form a tortuous air channel when the blocks are assembled in a stoker, said block being so shaped

as to provide tuyère openings at the fuel supporting end and through the side walls which communicate with various portions of said tortuous air channel.

5. A stoker comprising a side bar and a series of grate blocks mounted in step-like formation thereon, a longitudinal web forming a fuel supporting portion for each block, flanges on the under side of the web and walls on the upper portion of the block beneath, which form a tortuous air passage, and walls defining an air inlet and a tuyère opening communicating with said passage, which are so constructed and arranged that air must pass in cooling contact with an extensive surface area of the block before issuing through the tuyère opening.

6. A stoker comprising a side bar and a series of grate blocks mounted in step-like formation thereon, each block having walls defining an air inlet through its forward portion, transverse ribs on the fuel supporting portion of the block to catch and hold ashes thereon, flanges on the under side of the fuel supporting portion and walls on the block beneath which form an extensive air passage connecting with said inlet, and a tuyère opening from said passage adjacent the fuel supporting portion whereby air is caused to pass in cooling contact with a considerable surface of said block and become preheated before it issues into the fuel bed.

7. A stoker having in combination a side bar and a set of grate blocks mounted in step-like formation on said bar, each of said blocks being provided with transverse ribs on the fuel supporting portion to catch ashes and form a heat insulation for the block, a set of staggered flanges on the under side of said block, walls on the block beneath cooperating with said flanges to form a tortuous air passage, walls defining an air inlet to said passage, and a tuyère opening from said passage beneath the fuel supporting portion of each block, said parts being so arranged and constructed that air may pass upwardly through said inlet and thence through the passage in cooling contact with the flanges to the tuyère opening.

8. A stoker comprising a side bar and a series of grate blocks mounted in step-like formation thereon, the fuel supporting portion of each block having heat radiating flanges on its under side, walls on the block beneath which cooperate with said flanges to form a tortuous air passage and means defining an air inlet through the block opening into said passage and tuyère openings from said passage at the fuel supporting portion and side of the block which cause air to pass in contact with an extensive surface area of the block in traversing from the inlet to the tuyère openings.

9. A grate block for a stoker comprising a substantially horizontal web having at one

end parallel flanges depending from its under side and parallel transversely arranged ash retaining ribs on its upper side, a vertical side wall connected to the web and the ribs, and walls defining an opening through the block at the opposite end from the ribs and flanges.

10. A grate block for a stoker comprising a substantially horizontal web having at one end a series of ribs on its upper side and parallel transversely arranged flange on its under side, a vertical side wall connected to one side of the web, and walls defining an opening through the block, the walls and flanges being so shaped that, when a series of blocks are piled in step-like formation, the flanges will cooperate with the opening through the block and the walls to form lateral tuyères and a tortuous air passage issuing near the end of the block.

20 Signed at Worcester, Massachusetts, this 28th day of June, 1924.

IRVING ALBERT TAYLOR.
